UNITED STATES PATENT OFFICE

2,174,437

ELECTROLYTIC DEVICE

Joseph L. Collins, North Adams, Mass., assignor
to Sprague Specialties Company, North Adams,
Mass., a corporation of Massachusetts

Application September 21, 1936, Serial No. 101,841

3 Claims. (Cl. 220—44)

The present invention relates to electrolytic devices, and will be described in connection with electrolytic condensers, for which it is of particular usefulness.

5 I shall describe my invention in connection with so-called "wet" electrolytic condensers, although it is also applicable to so-called "dry" electrolytic condensers.

10 As the electrolyte of electrolytic condensers, particularly in the case of wet electrolytic condensers, is much affected by contaminations, such condensers are usually of the sealed-container type.

15 On the other hand, as during operation of the condensers gases are liberated at the electrodes, provision has to be made for the escape thereof.

20 Various venting means have been therefore suggested for such sealed condensers, many of which however have the drawback of permitting electrolyte to be carried away with the escaping gases, thus causing a loss of electrolyte of the condensers. The venting means described in the U. S. Patent No. 2,005,055 to Robert C. Sprague and John F. McCann overcome this difficulty and 25 have been widely used with good success.

25 In the construction described in the above patent, the container of the condenser is provided with a semi-permeable vent, which permits escape of the gases, but prevents escape of the electrolyte. 30 This is accomplished, for example, by providing an open-ended container with a metal cap as closure member, said cap being crimped securely to the container with the interposition of a semi-permeable gasket.

35 Such a semi-permeable gasket may be, for example, a fabric washer impregnated with wax or with other water-repellent material the washer being sufficiently porous to permit the escape of the gases but sufficiently impervious to the electrolyte to prevent its escape through the gasket with the liberated gases.

40 In the usual type of condensers and under usual operating conditions, the rate at which gas is liberated in the condenser is not in excess of 45 the rate at which these gases can pass through the above-described venting means.

45 However, there are types of electrolytic condensers, applications, and operating conditions, where the amount of gas liberated in the condenser and the rate at which such liberation takes place is too large for the above type of venting means to handle same, or which at least would require a considerable increase of the effective venting area of such means, involving 50 either an expensive construction or a consid-

erable increase in the dimensions of the condenser, both of which are obviously objectionable.

For example, in the type of condensers described in the copending application Ser. No. 743,469, filed September 10, 1934, of Preston 5 Robinson and Joseph L. Collins, now U. S. Patent #2,122,393 issued June 28, 1938, which condensers are now widely used as so-called "regulating condensers," there are operating conditions in the normal use of such condensers under 10 which a very large amount of gas is liberated in a very short time. Such regulating condensers, have their filming electrodes usually formed to medium voltages of about 250 to 350 volts, at which voltages the condensers show a small leakage current, for example in the case of a 16 15 microfarad condenser, a current of the order of 1.5 milliamps. At such a low leakage current the liberation of gases is small.

When such regulating condensers are submitted to high voltages, for example to 500 volts, they exhibit a sharp increase in leakage current without, however, showing any sparking or a substantial heating up of the filmed surface.

Such condensers are widely used in the filter 25 circuits of radio receiving sets, where they take up substantially the full plate voltage, for example 500 volts, at the instant the set is put into operation; however as the receiving tubes gradually heat up, the voltage across the condensers 30 gradually drops to a final value of 250 to 300 volts.

During such heating up of the receiving tubes, the very large leakage currents passing through the condensers, which for a 16 microfarad condenser may be initially as high as 50 milliamps and more, cause a correspondingly large amount of gas to be liberated, which during the first seconds after the set is placed in service may be 30 to 40 times as large as the gas liberated per second after the voltage across the condenser has 40 dropped to the normal operating voltage, i. e., 250 to 300 volts.

The purpose of my invention is to provide 45 venting means to safely handle even such suddenly liberated very large amounts of gases.

While I prefer to combine the novel venting means of my invention with the venting means of the above referred to patent, they can be also successfully used without the same and also in 50 combination with other types of known venting means.

According to my invention I provide a member, preferably in the form of a cap or diaphragm, which is provided with one or more fissures,

minute holes or similar type of openings having areas of the order of a few thousandths to a few ten-thousandths of an inch effective opening, and which in operation act as follows:

- 5 As long as the rate of liberation of the gases is small and thus no excess pressure builds up inside the container, communication from the interior of the container through the above fissure or fissures is blocked except as an adjunct to
- 10 the normal venting means and the gases escape through the latter, for example, through the vent gasket of the above-mentioned patent, although they may partly escape through the fissures after traversing through a portion of the
- 15 gasket.

However, if the rate at which the gases are liberated increases, pressure builds up in the container and this pressure causes such movement of the diaphragm as to expose the above fissure or fissures, and permit them to pass all of the gas liberated. As soon as the pressure on the diaphragm is reduced, the diaphragm returns into its original position and passage through the fissures is again substantially blocked, the diaphragm remaining in this condition as long as the rate of gas liberation is small.

In the preferred embodiment of my invention I provide the fissures on a cap member which is of somewhat similar shape as the crowned cap 30 described in the Patent No. 1,969,630 to Robert C. Sprague and Joseph L. Collins, although it is less domed and instead of increasing the strength of the container bottom, the doming is provided to help to bias the diaphragm in its normal 35 position.

Preferably the cap is provided with a substantially flat rim having fissures, whereby when pressure is built up in the condenser the flat rim is temporarily raised, which causes the fissures to be exposed. The resiliency of the cap causes it to assume its normal position when the pressure has been relieved, thus blocking the fissures.

The fissures can be applied to such a diaphragm member in various forms, for example 45 by drilling in the flat rims of the above cap a hole or preferably a plurality of uniformly distributed minute holes, for example of the size of about $\frac{1}{2}$ of an inch (although somewhat smaller or larger holes can be equally well used). 50 When the cap is crimped to the container these holes deform to form lineal fissures. The thickness of the material and the shape of the cap are so selected as to insure the desired resiliency and biasing of the cap.

55 In the drawing forming part of this specification:

Figure 1 is a vertical sectional view of a condenser in accordance with the invention;

Fig. 2 is an enlarged perspective view of the 60 cap member before it is secured to the container;

Fig. 3 is an enlarged section of the cap-end of the container showing the diaphragm raised under pressure.

Referring to Fig. 1, the condenser comprises a 65 cylindrical metallic container 10, which preferably constitutes the cathode of the condenser, and is provided at one end with a reduced neck or tubular extension 11. A seal provided in such tubular extension consists of a plug 12 of rubber 70 or other resilient material filling and extending slightly beyond both the inner and outer end of the tubular extension.

The plug 12 is provided with a central bore through which protrudes a support 15 of an anode 75 16, said support being secured in place by suit-

ably crimping the neck 11 around the plug 12 and the end of support 15. The container is almost completely filled with a suitable liquid electrolyte of the usual type, for instance with an aqueous solution of ammonium-borate.

The other end of the container is open and ends in a horizontal flange 34 and is adapted to receive a cap or diaphragm 20 (as shown in Fig. 2), preferably of metal, the cap comprising a central depressed portion 21 which fits inside of the 10 container at 22, and the middle portion 30 of which is slightly domed. The cap is furthermore provided with a flange having an inner horizontal portion 31 and an outer beveled portion 32.

The portion 31 of the flange is provided with 15 minute perforations, for example with four holes 40 of $\frac{1}{2}$ inch diameter which are equally spaced along the periphery of the cap.

The cap shown in Fig. 2 is secured to the container by interposing between the cap and the 20 flange 34 of the container, a washer or gasket 39 of wax-impregnated cloth. The rim 32 of the cap with the interposed washer 39 is spun over the flange 34 of the container, as shown in Fig. 1.

The holes 40 are thereby deformed into lineal 25 fissures 40a.

The anode 16 supported by the support 15 comprises an aluminum foil of relatively small thickness folded back and forth upon itself in the manner of accordion pleating, which is riveted 30 or otherwise secured to the support 15.

Suitable means (not shown) may be provided to properly space the anode 16 from the container 10 so as to prevent short-circuits between the same.

In operation the gas liberated at the electrodes normally escapes mainly through the pores of the vent gasket peripherally, as shown by the arrows in Fig. 3, although some gas also passes via a portion of the gasket through the fissures 40 40a.

When for some reason or other, for example in the case of the above referred to regulating condensers, a sudden increase in gas liberation takes place, pressure builds up in the condenser which 45 causes the flange portion 31 of the cap to be raised, and which thereby permits a rapid escape of the gas through the fissures 40a (see Fig. 3).

As soon as this increased pressure is relieved the cap 20, due to its resiliency, returns the 50 flange portion 31 to its normal position.

It should be well understood that the venting means in accordance with my invention successfully permit the escape of excessive amounts of gases, whatever may be the reason for their liberation.

For example, if a condenser because of unusually high ambient temperatures or sustained abnormally high voltages, assumes for a considerable length of time a higher temperature than 60 is the temperature for which it has been designed, such increased condenser temperature will result, because of increased current, in an increased liberation of gases. The venting means of my invention will in such case fully safeguard 65 the continued escape of such gases without any injury to the condenser; whereas other types of venting means unless they also permit the escape of the electrolyte would be unable to handle such large amounts of gas, in view of which destruction of the condensers may take place.

For example, in making tests with condensers operated for continued periods at a hundred times their normal leakage current, I have found that condensers using, for example, the vent gaskets 75

of the above referred to patent, were destroyed after relatively short time periods, whereas condensers having venting means in accordance with the invention remained intact indefinitely.

5 While I have described my invention in connection with a specific construction and in a specific application, I do not wish to be limited thereto, but desire the appended claims to be construed as broadly as permissible in view of the prior art.

10 What I claim is:

1. Venting means for electrolytic devices comprising a resilient cap member provided with a fissured flange portion, a gasket cooperating with

15 said flange portion to normally close the fissures, said flange portion being partly lifted from said gasket by pressure of accumulated gases to permit the gas to escape through said fissures, said cap member being biased by its own resiliency to assume its normal position when said gas pressure is relieved.

20 2. An electrolytic condenser comprising a container, a diaphragm member having a fissured

portion and a gasket normally closing the fissures, said member and gasket being crimpedly secured to said container, said fissured diaphragm portion being adapted to be raised from said gasket under the pressure of gases liberated within the condenser to permit escape of said gases through said fissures, said diaphragm member having a resiliency sufficient to return the fissured portion to its normal position.

5 3. In an electrolytic condenser, in combination, 10 a metallic container open at one end, a metal diaphragm forming a closure member therefor, said diaphragm having a substantially flat fissured flange portion and a domed central portion, a semi-pervious gasket interposed between 15 the container end and the flat diaphragm portion normally closing said fissures, said fissured portion being raised when gas pressure is built up within the container to relieve the gas pressure, and being returned by the resiliency of the 20 diaphragm when pressure has been relieved.

JOSEPH L. COLLINS.
